UNITED STATES PATENT OFFICE.

HENRY W. STARKWEATHER, OF NEW HAVEN, CONNECTICUT, ASSIGNEE TO WINCHESTER REPEATING ARMS CO., OF NEW HAVEN, CONNECTICUT, A CORPORATION.

MUSHROOM-BULLET.

1,077,564.

Specification of Letters Patent.

Patented Nov. 4, 1913.

Application filed September 13, 1913. Serial No. 789,596.

To all whom it may concern:

Be it known that I, HENRY W. STARKWEATHER, a citizen of the United States, residing at New Haven, in the county of New Haven and State of Connecticut, have invented a new and useful Improvement in Mushroom-Bullets; and I do hereby declare the following, when taken in connection with the accompanying drawings and the characters of reference marked thereon, to be a full, clear, and exact description of the same, and which said drawings constitute part of this application, and represent, in—

Figure 1, a view in side elevation of a mushroom bullet constructed in accordance with my invention with a portion of the jacket broken away. Fig. 2, a detached view in side elevation of the sheet-metal tip. Fig. 3, a view corresponding to Fig. 1, showing one of the modified forms which my invention may assume. Fig. 4, a detached view in side elevation of the jacket tip of Fig. 3.

My invention relates to an improvement in that class of mushroom bullets having two-part sheet-metal jackets swaged upon a soft-metal core, the object being to produce a bullet of superior mushrooming effect.

With this end in view my invention consists in a mushroom bullet having certain details of construction as will hereinafter be described and pointed out in the claims.

In carrying out my invention as herein shown, I employ a jacket-body, 3, and a jacket-tip, 4, made independently of each other from relatively hard sheet-metal and concurrently swaged upon a soft-metal core, 5, which solidly fills the two-part jacket thus produced. The said jacket-body is secured in place by being swaged upon the core. For securing the jacket-tip 4 in place its open inner end is deeply indented to form a plurality of corresponding retaining fingers, 6, having flaring anchor-ends or terminals, 7, these fingers, 6, being separated by wedge-shaped extrusion openings, 8, which alternate with the fingers, 6. Under the action of the swaging dies, the extreme edge,

9, of the jacket-body, 3, crowds the inner ends of the fingers, 6, inward until the exterior surface of the jacket-body forms a continuous line with the exterior surface of the jacket-tip, whereby the inner ends of the fingers are slightly set inward and the fingers gripped by and between the edge of 55 the jacket and the surface of the core, 5.

The swaging of the jacket-body and jacket-tip upon the core, as described, results in the formation of regular shallow cavities, 10, in the exterior surface of the bullet, due to the bending inward of the ends of the fingers, 6. Those portions of the extrusion openings, 8, that extend beyond the edge 9 of the jacket-body when the tip is in place therein, have portions of the 65 soft-metal core, 5, exuded into them so as to form small triangular areas 11 of soft metal alternating with the shallow cavities, 10, aforesaid.

In the modified construction shown by 70 Figs. 3 and 4 of the drawings, the hollow jacket-tip, 12, has its open inner edge cut to form four narrow retaining fingers, 13, having flaring anchor ends, 14, and separated by blunt-ended extrusion openings, 75 15, the construction being otherwise the same as described in Figs. 1 and 2.

I claim:

1. A mushroom bullet having a soft metal core, a jacket-body applied thereto, and a 80 hollow jacket tip the open end of which is indented to form a plurality of retaining-fingers alternated with extrusion-openings, the ends of the fingers being frictionally held between the core and the swaged edge 85 of the jacket, and the outer portions of the said extrusion openings being filled with extruded portions of the soft metal of the core which form interrupted areas of soft metal on the outside of the bullet. 90

2. A mushroom bullet having a soft metal core, a jacket-body, and a hollow jacket-tip the open inner end of which is indented to form alternating retaining-fingers having anchor-ends and extrusion-openings, the 95 ends of the said fingers being frictionally

held between the surface of the core and the swaged edge of the jacket and the outer portions of the said openings being filled with extruded portions of the soft metal of the core which form interrupted areas of soft metal on the outside of the bullet.

In testimony whereof I have signed this

specification in the presence of two subscribing witnesses.

HENRY W. STARKWEATHER.
